WILLIAM P. WOOD, OF PAWTUCKET, RHODE ISLAND, ASSIGNOR TO JENCKES SPINNING COMPANY, OF PAWTUCKET, RHODE ISLAND, A CORPORATION OF RHODE ISLAND.

WINDING-MACHINE.

1,352,930.

Specification of Letters Patent. Patented Sept. 14, 1920.

Application filed January 3, 1919. Serial No. 269,461.

To all whom it may concern:

Be it known that I, WILLIAM P. WOOD, a citizen of the United States, residing at Pawtucket, in the county of Providence and 5 State of Rhode Island, have invented certain new and useful Improvements in Winding-Machines; and I do hereby declare the following to be a full, clear, and exact description of the invention, such as will enable others skilled in the art to which it 10 pertains to make and use the same.

The invention relates to bunch building mechanism for winding machines such as are used for winding yarn on shuttle bobbins.

Bunch building mechanism of this character as usually constructed is provided with a yarn controller finger which should be moved by the operator into position to engage 20 the yarn between the traverse yarn guide and the bobbin when starting the winding of a bobbin. If the operator fails to properly set the controller finger when starting the machine, a bobbin will be wound 25 without the bunch requisite for avoiding defects in the cloth woven by the loom in which the bobbin is to be used. This is a serious objection to the mode of operation of the bunch building mechanisms, and frequently 30 results in defective fabric and loss due to carelessness on the part of the winding machine operators.

It is the object of the present invention to insure the proper and uniform building 35 of the bunch by the bunch building mechanism, so that the winding of defective bobbins, due to carelessness on the part of the operator, is prevented. To this end the invention contemplates so controlling the 40 winding mechanism that it cannot operate to wind the bobbin unless the bunch building mechanism has been adjusted or set to build the bunch at the beginning of the winding operation. This insures the proper setting 45 of the bunch builder at the beginning of each winding operation and the building of a bunch upon every bobbin wound on the machine. The winding mechanism is preferably thus controlled by providing 50 means which, upon the stopping of the machine at the completion of a bobbin, will retain the stop mechanism of the machine in stopping position until the yarn controller finger of the bunch building mechanism is 55 moved by the operator into active position

at the beginning of the succeeding bobbin. It is desirable that this mechanism should be inactive during the winding of a bobbin, so that it will not interfere with the normal operation of the stop mechanism, and should 60 again become active at the beginning of the winding upon the succeeding bobbin. Means is therefore provided through which the insertion and removal of the bobbin controls the action of the means which in turn controls 65 the starting of the winding mechanism.

The preferred form of the invention is shown in the accompanying drawings embodied in the bunch building mechanism 70 shown and described in application Serial No. 242,674, June 29, 1918. In the drawings, Figure 1 is a plan view showing so much of a winding machine as is necessary to illustrate the application of the present 75 invention thereto; Fig. 2 is a side elevation of parts shown in Fig. 1; Fig. 3 is a similar view showing some of the parts in different position; and Fig. 4 is a sectional elevation.

In the drawings the invention is shown applied to the well-known Universal winding machine for winding bobbins such as are used in automatic looms. As shown, the winding spindle 2 is provided with the center 4 and the lugs 6 for engaging the end of the bobbin. The outer end of the bobbin is engaged by the spring-pressed support 8 which may be forced back in the bracket 10 in inserting and removing the bobbins. The yarn is guided during the winding of the bobbin by a traverse yarn guide 12 mounted on the reciprocating traverse bar 14. The driving mechanism for the machine is thrown into and out of operation 90 by a starting rod 16 which is rocked by the operator to throw the driving mechanism into operation, and which is latched in driving position by a latch lever 18 arranged to engage an arm 20 projecting from the rod. When the latch is disengaged from the arm the rod is rocked to throw out the driving mechanism and stop the machine through a spring (not shown). The machine is automatically stopped upon break- 95 age of the yarn through a lever 22, one arm of which is provided with an eye through which the yarn leads, and the other arm of which is provided with a lug 24 arranged to engage a lever 26 which is pivoted on 100 105 110

the latch 18, and is provided with an arm 28 adapted to be brought into and out of the path of a collar 30 secured to the traverse bar. During the operation the tension on 5 the yarn holds the lever 22 in the position indicated in Fig. 4, so that the arm 28 of the lever 26 is out of the path of the collar 30. When the tension on the arm is relieved, as by the breaking of the yarn, the lever 10 22 will swing about its pivot, and the lug 24 will rock the lever 26 so that its arm 28 will be carried up into the path of the collar 30. When this occurs the collar 30 will, during reciprocation of the traverse 15 bar, strike the arm 28 and disengage the latch 18 from the arm 20 on the starting rod, so that the rod will be released and the machine will be stopped.

As thus far described, the machine is the 20 same in construction and mode of operation as the well-known universal winding machine.

The bunch building mechanism shown in the drawings comprises a yarn controller 25 finger 32 which is normally retained in retracted inactive position, as indicated in Fig. 1, by a spring 34. At the beginning of the winding operation this finger is moved forward into the position indicated 30 in Fig. 4, so that it will engage the yarn leading from the traverse yarn guide to the bobbin, and will cause the yarn to be wound in the form of a bunch within the groove 36 in the bobbin. The controller finger is 35 retained in active position by a vertically movable latch bar 38 which is forced upward by the spring 40, and is provided at its lower end with a transverse arm 42 carrying the contact screw 44 arranged to be engaged by the bunch of yarn built up in the 40 groove 36. When the bunch has been wound to the size determined by the adjustment of the contact screw, it will force the latch bar 38 downward until the finger 32 is released, when the finger will be retracted into 45 its inactive position by its spring 34, and in this movement act on the cam shaped upper end of the latch bar to press it downward and remove the contact screw 44 from 50 engagement with the yarn during the continued winding of the bobbin.

In applying the present invention to the winding machine and bunch building mechanism above described, means is provided 55 which is rendered active upon the removal of a bobbin for retaining the stop mechanism in stopping position until the yarn controller finger has been moved into active position. In the construction shown, this 60 means consists of a vertically movable latch bar 46 adapted to slide in guide-ways formed in the arms of a bracket 48, and arranged to engage a shoulder 50 formed on a collar 52 which is secured to the lever 65 22 of the stop mechanism. The latch bar

is forced downward in a direction to engage the shoulder on the lever 22 by a spring 54, and is raised into inactive position against the tension of the spring by the engagement of the arm 42 of the latch bar 38 70 with a pin 56 which projects from the latch bar 46. The upper end of the bar 46 is slotted at 58 to form a hook 60 adapted to overlie and engage the upper arm of the bracket 48 when the bar is in its raised position, and to support the bar with its lower end out of active position. The spring 54 tends to draw the upper end of the bar laterally into position for its hooked end to engage and rest on the arm of the bracket. 80 Movement of the upper end of the bar into this position is prevented whenever there is no bobbin in the machine by a plate 62 mounted on the end of the winding spindle 2 and pressed forward into engagement with 85 the head of a screw 64 on the bar 46 by the springs 66. When a bobbin is in position in the machine, it presses the plate 62 back, as indicated in Fig. 3, so that the spring 54 is free to draw the upper end of 90 the latch bar 46 into position to engage and be retained by the upper plate of the bracket 48.

Assuming that a bobbin has been inserted, and the controller finger 32 moved into position, and the machine started, to begin the winding of the bobbin, the parts will be in the position indicated in Figs. 3 and 4. As the winding continues, the controller finger will guide the yarn into the groove 36 until the bunch built therein depresses the latch bar 38 and releases the controller finger. When this occurs, the arm 42 of the latch bar 38 will move down away from the pin 56, and the latch bar 46 will move downward until the hook 60 at its upper end rests on the upper plate of the bracket 48, where it will remain until the winding of the bobbin has been completed and the machine has been automatically stopped by the usual 110 mechanism. When the bobbin is removed, the plate 62 will move forward into the position indicated in Fig. 2, and in so doing will engage the screw 64 and disengage the hook 60 on the bar 46 from its supporting arm, thus permitting the bar to move down into position to engage the shoulder 50 on the lever 22 of the stop mechanism, this lever having moved over into stopping position when the tension on the 120 yarn was relieved. The latch bar 46 will now lock the stop mechanism in stopping position until the controller finger 32 is swung into active position at the beginning of the succeeding winding operation after 125 a fresh bobbin has been inserted in the machine. When the controller finger is moved into active position, the upward movement of the latch bar 38 and its arm 42 will disengage the latch bar 46 from the 130

lever 22, so that the lever may move into driving position under the tension of the yarn. The insertion of the bobbin will move the plate 62 back away from the head 5 of the screw 64, so that the return of the latch bar 46 to active position will be prevented by the hook 60 at its upper end until the winding of this bobbin has been completed and the bobbin is removed. The 10 latch bar will not therefore interfere with the normal automatic action of the stop mechanism during the winding of the bobbin, but will prevent the starting of the winding upon a fresh bobbin until the 15 bunch building mechanism has been properly adjusted by the operator.

While the invention has been shown and described as applied to the bunch building mechanism of the application above referred 20 to, it will be understood that it is not confined in its application to this bunch building mechanism, but may be applied to other forms of bunch building mechanism. It will also be understood that while it is preferred to employ the specific construction 25 and arrangement of parts in applying the invention to the bunch building mechanism shown and described, this construction and arrangement is not essential to the broader 30 features of the invention, but may be varied or modified as found desirable or best suited to the construction and arrangement of parts in the winding mechanism and bunch building mechanism to which it is to be applied.

What is claimed is:—

1. A winding machine, having, in combination, winding mechanism, bunch building mechanism, and means for controlling the 40 starting of the driving mechanism for the winding mechanism from the bunch building mechanism.

2. A winding machine, having, in combination, winding mechanism, bunch building 45 mechanism, and means for preventing the operation of the winding mechanism to wind the bobbin, which is rendered inactive in rendering the bunch building mechanism active.

50 3. A winding machine, having, in combination, winding mechanism, stopping mechanism therefor, bunch building mechanism, and means for maintaining the stopping mechanism in stopping position which is rendered inactive upon the setting of the bunch building mechanism.

4. A winding machine, having, in combination, winding mechanism, a bunch building yarn controller, mechanism for preventing the 60 operation of the winding mechanism to wind the bobbin which is rendered inactive in setting the yarn controller to build a bunch at the beginning of the winding.

65 5. A winding machine, having, in com-

bination, winding mechanism, stopping mechanism therefor, a bunch building yarn controller, and means for maintaining the stopping mechanism in stopping position which is rendered inactive in setting the 70 yarn controller to build a bunch at the beginning of the winding.

6. A winding machine, having, in combination, winding mechanism, stopping mechanism therefor, a bunch building yarn 75 controller, a latch for retaining the stopping mechanism in stopping position, and means for releasing the latch when the yarn controller is moved into bunch building position at the beginning of the winding. 80

7. A winding machine, having, in combination, winding mechanism for winding yarn on a bobbin, stopping mechanism therefor, a bunch building yarn controller, means for retaining the stop mechanism in stop- 85 ping position which is rendered inactive upon movement of the controller into bunch building position and remains inactive until again rendered active by an act of the operator after the completion of that bobbin. 90

8. A winding machine, having, in combination, winding mechanism for winding yarn on a bobbin, stopping mechanism therefor, a bunch building yarn controller, and means rendered active upon the removal of 95 the bobbin and rendered inactive upon the movement of the controller into bunch building position for retaining the stop mechanism in stopping position.

9. A winding machine, having, in combination, winding mechanism for winding yarn on a bobbin, stopping mechanism therefor, a bunch building yarn controller, a latch for retaining the stopping mecha- 100 nism in stopping position, means for ren- 105 dering the latch active upon the removal of a bobbin, and means for rendering the latch inactive upon the setting of the controller to build a bunch and for maintaining it inactive until the removal of the bobbin. 110

10. A winding machine, having, in combination, winding mechanism for winding yarn on a bobbin, stopping mechanism therefor, a bunch building yarn controller, a latch for retaining the stopping mechanism 115 in stopping position, means for releasing the latch when the yarn controller is moved into bunch building position at the beginning of the winding, and means for thereafter main- 120 taining the latch inactive until again ren- dered active by an act of the operator after the completion of that bobbin. 115

11. A winding machine, having, in combination, winding mechanism for winding yarn on a bobbin, stopping mechanism 125 therefor, a bunch building yarn controller, a latch for retaining the stopping mecha- nism in stopping position, means for releas- 130 ing the latch when the yarn controller is moved into bunch building position at the

beginning of the winding, and means rendered active and inactive by the removal and the insertion of a bobbin for maintaining the latch inactive when released by the setting of the yarn controller.

12. A winding machine, having, in combination, winding mechanism for winding yarn on a bobbin comprising a winding spindle, a spring-pressed plate on the spindle 10 arranged to be moved by the end of an in-

serted bobbin, stopping mechanism, a bunch building yarn controller, a latch for retaining the stopping mechanism in stopping position rendered active by the plate when freed by the removal of a bobbin, and means for rendering the latch inactive upon movement of the yarn controller to bunch building position. 15

WILLIAM P. WOOD.

Correction in Letters Patent No. 1,352,930.

It is hereby certified that in Letters Patent No. 1,352,930, granted September 14, 1920, upon the application of William P. Wood, of Pawtucket, Rhode Island, for an improvement in "Winding-Machines," an error appears in the printed specification requiring correction as follows: Page 3, line 122, claim 10, strike out the words "is completed"; and that the said Letters Patent should be read with this correction therein that the same may conform to the record of the case in the Patent Office.

Signed and sealed this 30th day of November, A. D., 1920.

[SEAL.]

L. B. MANN,

Acting Commissioner of Patents

Cl. 242—31.
